Filed Oct. 26, 1971, Ser. No. 192,696

Term of patent 3½ years

Int. Cl. D21—01

U.S. Cl. D34—15 GG

The figure is a perspective exploded view of an interlocking cushion tile showing our new design.

In the drawing the unseen edges are the same as those shown. The characteristic feature of our design resides in the particular configuration of the teeth shown.

We claim:

The ornamental design for interlocking cushion tile, as shown and described.
